UNITED STATES PATENT OFFICE.

JACOB J. PLUCKER, OF PHILADELPHIA, PENNSYLVANIA, ASSIGNOR TO
CATHERINE A. PLUCKER AND HOWARD W. PLUCKER.

FIREPROOF CASING.

SPECIFICATION forming part of Letters Patent No. 734,603, dated July 28, 1903.

Application filed February 11, 1903. Serial No. 142,884. (No model.)

To all whom it may concern:

Be it known that I, JACOB J. PLUCKER, a citizen of the United States of America, and a resident of 6820 Paschall avenue, Philadelphia, Pennsylvania, have invented certain new and useful Improvements in Fireproof Casings, of which the following is a specification.

My invention relates to certain new and useful improvements in elevator-casings, and has for its object to produce a casing which under normal conditions is open for the admission of light and air to the shaft and which may be closed simultaneously for all the floors of a building to make the casing fireproof in case a fire should occur on any floor of the building, thereby preventing the fire from spreading to the other floors of the building by being drawn up through the elevator-shaft and at the same time allowing persons who may be on the upper floors of the building to be carried down in safety by the elevator.

While I have shown in this application my casing as being applied to an elevator-shaft, it will of course be apparent that the same may be applied to a stairway or light or other shaft, if desired.

Referring to the drawings, wherein the same reference-numeral is used to designate the same part wherever it occurs, Figure 1 is a vertical elevation of my invention as applied to an elevator-casing, showing three floors of a building. Fig. 2 is a vertical section showing the means for operating the shutters. Fig. 3 is a detached view of the telescoping cornice and foot-plates for the supporting-posts of the casing, showing the shutters closed and in operative relation to the cornice and foot-plates. Fig. 4 is a detail view showing the means by which the shutters are mounted in their supporting-posts. Fig. 5 is a view similar to Fig. 4, taken at right angles thereto. Fig. 6 is a transverse horizontal section showing the means of attaching the operating-pinion and the shutters together and also showing how the shutters are pivoted in their supports. Fig. 7 is a view similar to Fig. 2, but showing a slightly-modified form of the operating mechanism. Fig. 8 is a side elevation of my casing when used in connec-

tion with a stairway. Fig. 9 is a view similar to Fig. 8, taken at right angles thereto, showing the doors at each floor. Fig. 10 is a section view through the casing.

Referring to the drawings, 1 is a casing extending through the several floors of a building provided with doors 2 2 2, one on each floor. The casing consists of a series of posts 3 3, in which are pivoted a series of shutters 4. The posts 3 are shown in section in Fig. 6, from which it will be seen that these posts are in the form of channel-irons, and on the interior edges of the side walls of these posts I provide slots 5, the bottoms of which are 65 of semicircular form and which are closed by straps 6, provided with semicircular slots 7 cut therein, which when the straps are in position register with the slots 5, the straps being held in position by the screws 8 or 70 other suitable means. These two semicircular notches will together form a round hole, in which I mount the stems of the shutters and in which the stems are adapted to rotate when the shutters are opened or closed.

In the form of shutters shown in this application the shutters are made from plates of sheet metal and bent in the form shown best in Figs. 3 and 7, the stems of the shutters being preferably square in cross-section 80 and formed by bending up a portion of the blank from which the shutters are made, suitable cuts being made in the blank on each side for this purpose. Through the center of each shutter-blank I form a longitudinal stiffening-rib 55 by bending out of the central portion of the blank a V-shaped groove parallel with the longitudinal axis of the blank. The rib extends also to the extremity of each extending portion of the blank from which 90 the stems are made and forms two sides of the square stems and insures the axial alignment of the stems. These square stems 9 project into the notches formed by the slots 5 and 7. The stems of the shutters project 95 in from the opposite side walls of the channel-irons and are united together by a gear 10, having square stems 11, which are inserted in the openings formed in the stems 9 of the shutters. By this construction it will 100 be seen that the shutters are secured to the pinion 10, so that they will rotate in unison

with the pinion, and by using a square stem the connection is very cheaply made and at the same time will allow for the expansion and contraction of the parts.

- 5 12 represents a pair of plates each provided on one end with a box-like structure 13. Each of these plates is provided with the internal flange portion 14, and these plates form the cornice of the casing on each floor.
10 These plates are constructed of such a length that they will overlap, so that they may be used in connection with shutters of different lengths without the necessity of special fitting.

- 15 15 15 are slots formed in the sides of the boxes 13, and to these boxes the posts 3 are bolted to form the casing construction. By having the sides of these boxes slotted in the manner shown it is possible to use posts of 20 the same length in a building wherein the heights of the ceilings of the different floors vary, as by the use of these slotted boxes the height of the top of the cornice may be adjusted.

- 25 16 16 are a pair of plates similar to the plates 12 and provided with boxes 17 17, similar to the boxes 13, these plates forming the foot-plates of the casing on each floor. The boxes 17 are provided with slots 18 for the 30 same purpose as the slots 15 in the boxes 13.

- 35 Mounted on top of the plates 3 3 are brackets 19, which support shafts 20, 21, and 22, these shafts being geared together by means of the beveled gears 23, 24, 25, and 26. 40 Mounted on the shaft 20 is a gear 27, which when operated will rotate the shafts 20, 21, and 22. Meshing with the gear 27 is a worm 28, carried by a vertical shaft 29, extending down alongside the elevator-casing through 45 all the floors of the building, and this shaft is supported at its bottom in suitable supporting-bearings 30, and in a bracket 31 is a suitable bearing for the top of the shaft. This shaft on each floor is provided with a hand-wheel 32 or other suitable means by which the shaft may be rotated.

- 33 represents arms carried by the shafts 20, 21, and 22, and 34 are rods connected to the arms 33 by means of the link 35. The rod 34 50 extends from the top to the bottom of the building and at each floor is provided with a rack 35^a, which meshes with the gears 10, carrying the shutters. The gears 10 are so set in relation to each other that when the 55 rack is operated all the shutters will move simultaneously. In order that the shutters when closed may be put under tension to hold their edges together securely in the form shown in Fig. 2, I provide the rack 35^a at each 60 end with a lug 36, through which the rod 34 loosely passes, and secure to the rod 34 below each lug 36 a collar 37. I interpose between each lug and collar a spring 38, whereby when the rod 34 is drawn up to close the shutters 65 the shutters will move until their edges are in contact, and then further moving of the rod will compress the springs 38. In order

to limit the movement of the lugs of the rack due to the springs, I preferably place collars 39 on the rod 34 above the lugs 36.

70 40 is an arm projecting out from the shaft 20, and mounted on this arm is an adjustable weight which may be set on the arm to balance the weight of the rod 34 and its connected parts and act as a counterweight, so that the shutters may be easily and readily 75 closed by operating the shaft 29.

In order to keep the casing cool, so that persons may pass up and down the interior of the casing while a fire is in progress, I extend 80 around the casing outside of the cornice on each floor pipes 42. These pipes are all connected to a supply-pipe 43, provided with a valve 44, which has a sprocket-wheel 45 thereon. Mounted on the shaft 21 is a sprocket-wheel 46, and 47 is a sprocket-chain connecting the sprocket-wheels 45 and 46, whereby when the shafts are operated to close the shutters of the casing the valve will be opened and supply water from suitable perforations 85 in pipes 42 down the sides of the casing, so as to keep the interior of the casing cool.

In the form of my invention shown in Fig. 7, 48 is a rod which is connected to the link 35 in the same manner that the rod 34 is connected to the link, and 49 is a sleeve connected to the lower end of the rod 48 in any suitable manner, as by set-screws 50. 51 is a rack which operates the gears 10, and this rack is secured at its upper end in the sleeve 95 by any suitable means, as by set-screw 52. The rack for each set of shutters is connected to the adjacent racks in the same manner as the rack 51 is connected to the rod 48. By this means the racks for each set of shutters may be so adjusted in relation to each other that the shutters will all be closed by the same amount of movement of the arm 33.

The structure above described is very cheap to manufacture and set up—in fact, is no more expensive than the wrought-iron grill heretofore used in connection with elevator-casings and the like—and it is open under normal conditions to allow all the light and air necessary to freely enter the shaft. When, however, a fire occurs anywhere in the building, it is only necessary to rotate the shaft 29, which through the worm-gear will rotate the shafts 20, 21, and 22 and through the arms 33 will operate to close all the shutters 100 on all the floors and make the casing fire-proof, thus cutting off all communication from the floors with the shaft, so that a fire can have no chance to spread through the building by means of the shaft, as is often the case. Furthermore, people on the upper floors of the building may be carried down by the elevator in perfect safety, as a fire in the building can in no way get into the shaft.

105 In Figs. 8, 9, and 10 I have shown my casing as inclosing a stairway, the shutters forming the casing being operated in the same manner as previously described. I have shown the casing as being provided with doors 110

60, through which persons may obtain access to the stairs. Preferably these doors are each provided with means for closing them all simultaneously, which means is controlled by 5 the operation of the vertical operating-shaft 29. I have indicated such a means as a cylinder 61, pivoted on a bracket 62 and provided with a piston and piston-rod 63, connected with each door. 64 is a flexible hose connecting one end of the cylinder with a vertical pipe 65. This pipe is connected to a suitable source of air or other pressure and is provided with a valve operated in a similar manner to the valve 44, controlling the 15 water-supply, whereby when the shutters are closed air under pressure will be introduced into the cylinder and will act to close the doors, it being possible, however, to open the doors against the pressure, so that any one 20 may enter the casing.

Having thus described my invention, what I claim as new, and desire to secure by Letters Patent, is—

1. In an elevator or similar shaft, the combination with a series of posts surrounding the shaft, sets of movable shutters interposed between the posts, gears on the shutters, a rack meshing with the gears of each set of shutters, means connecting the racks together, and means operating to move all the racks in unison whereby all the sets of shutters may be opened and closed simultaneously.
2. In an elevator or similar shaft, the combination with a series of posts surrounding the shaft, sets of movable shutters interposed between the posts, gears on the shutters, a rack meshing with the gears of each set of shutters, means connecting the racks together, 40 and means consisting of shafts connected together and operated by a vertical shaft extending from the top to the bottom of the building, whereby all the shutters may be opened and closed simultaneously by oper-

ating the vertical shaft from any floor of the 45 building.

3. In an elevator or similar shaft, the combination with a series of posts surrounding the shaft, the posts being provided with semi-circular notches, straps provided with semi-circular notches adapted to be secured to the posts, the notches in the straps and posts forming bearings for the sets of shutters, sets of shutters, each shutter being provided with square stems adapted to rotate in the bearings formed by the notches in the posts and straps, and means adapted to operate all the sets of shutters simultaneously.

4. In an elevator or similar shaft, the combination with a series of posts surrounding the shaft, sets of movable shutters interposed between the posts, gears on the shutters, a rack for each set of shutters adapted to mesh with the gears of that set, a rod extending the length of the shaft to which the racks are 65 connected, mechanism at the top of the shaft for operating the rod, and a shaft extending the length of the elevator-shaft adapted to operate the rod-operating mechanism, whereby all the sets of shutters may be operated 70 simultaneously.

5. The combination with a series of shutters pivoted in suitable frames, gears on the shutters, a rack meshing with the gears, a rod, a collar secured to the rod through 75 which the rack loosely passes, a second collar fast on the rod, and a spring between the collars, the parts being so constructed that when the rod is moved the rack will operate to close the shutters and hold the same together under tension.

Signed by me at Philadelphia this 5th day of February, 1903.

JACOB J. PLUCKER.
